UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed May 17, 1926. Serial No. 109,740.

This invention relates to mining machines and more particularly to the cutting mechanisms of mining machines of the class known as arcwalls machines, and as particularly disclosed herein the invention is embodied in a 5 arcwalls type of machine of the universal or combined horizontal and vertical cutting type.

In the present day mounted mining machine which embodies a truck provided with appropriate running gear and generally adapted to be propelled along tracks laid in the mine passages, power operated cutting mechanisms are provided which include 10 means for actuating the cutting elements to effect the cutting operation thereof and means for swinging the cutter bar upon which the cutting elements travel to effect the making of arcuate cuts and to adjust the 15 bar to the positions in which it may be fixed during the making of entering or "sumping" and withdrawing cuts. Moreover, since the 20 machines are in certain preferred forms provided with but a single motor which not only 25 operates the cutting mechanism, but also provides for the feeding of the machine during 30 propulsion about the mine as well as during cutting, it is desirable to provide means for 35 wholly disconnecting the cutting mechanism 40 from the operating motor so that while the 45 machine is moving around the mine it may 50 be possible to leave the bar dead and so avoid 55 serious injury to miners who may be in the 60 vicinity of the machine while it is being 65 moved. It is furthermore highly desirable 70 in view of the relatively large size of 75 machines of this type to be able to swing the 80 cutter bar by power without necessity of 85 operating the cutting elements, for by swinging 90 the bar turns into entries opening off of the 95 main passageways may be much more readily 100 negotiated.

Among the objects of the present invention is the provision of an improved cutting mechanism which is particularly adapted to meet the several problems outlined. More particularly, it is an object of the invention to provide an improved cutting mechanism including means for actuating the cutting 50 elements, and means for swinging a cutter

bar supporting the cutting elements, the mechanism having provision whereby the control of the cutting elements and the bar swinging mechanism may be effected in an improved and highly advantageous manner. 55 Further, it is an object of the invention to provide in such a combination means for wholly disconnecting the cutting mechanism from an actuating motor and still more specifically, it is the object of the present invention to provide improved unitary control 60 means governing the connection of the cutting mechanism with a source of power, the swinging of the bar and the actuation of the cutting elements in a predetermined sequence 65 and thereby providing a maximum of safety for the machine runner and all others in the neighborhood of the machine. Other objects and advantages of the invention will 70 subsequently appear.

In a preferred embodiment the invention may comprise a pivotally mounted cutter bar carrying orbitally movable cutting elements and means for controlling the swing of the bar and the actuation of the cutting elements 75 in such manner that power will be applied to effect orbital movement of the cutting elements only after power connections have been established permitting swing of the bar. From another aspect the invention comprises 80 in addition to the features set forth the provision of clutch means for connecting the entire cutting mechanism so far mentioned to or disconnecting it from a source of power 85 and so relating the control of the last mentioned clutch means and the control mechanism for the remaining portions of the cutting mechanism that the power connection last mentioned will be the first to be established and the last to be interrupted. More 90 specifically, the invention may comprise means for connecting the cutting mechanism with the source of power, means for making available bar swinging power, and means for 95 supplying power to actuate the cutting elements in the sequence set forth, and disconnecting them in reverse sequence, and in a preferred form the mechanism for accomplishing these results may comprise a single cam whose movement in opposite directions 100

automatically effects the connections and disconnections specified. The foregoing statement of certain aspects of the invention is not intended to be all-inclusive and other aspects of the invention will hereinafter appear.

In the accompanying drawings in which for purposes of illustration one illustrative embodiment of the invention is shown,

10 Fig. 1 is a plan view with parts broken away of the cutting end of a mining machine in which the illustrative embodiment of the invention is incorporated.

15 Fig. 2 is a central longitudinal vertical section on the line 2—2 of Figs. 1 and 3.

20 Fig. 3 is a view partially in horizontal section and taken on different planes, showing details of the mechanism constituting the illustrative embodiment.

25 Fig. 4 is a section on the line 4—4 of Fig. 2 and is a vertical transverse section on this line.

30 In the drawings the illustrative embodiment of the invention is disclosed as incorporated in a machine of the so-called universal type in which provision is made for the insertion of shearing as well as horizontal kerfs and in which the plane of the kerfs may be adjusted. In the drawings 1 represents a suitable wheel supported frame one of whose supporting wheels is shown at 2. The frame 1 supports a mining machine shown only in part and generally designated 3 which comprises a body 4 shown only in 35 part and rotatable upon a horizontal axis in trunnions 5 of which the forward one is shown. Rotatable about the axis of the trunnion 5 is the cutting mechanism generally designated 6 and to this cutting mechanism power is supplied by a shaft 7 which is actuated by a motor forming a portion of the machine 3, but not illustrated as its details are not involved in the present invention. The cutting mechanism 6 comprises a casing 6^a rotatable as previously stated upon a horizontal longitudinally extending axis and comprising a main body portion 8, a top cover 9 and a bottom bearing ring 10. The bottom of the casing is closed by a rotatable 40 cutter bar support 12 to which a cutter bar 13 provided with a circulating cutter chain 14 is rigidly secured. A cutter chain driving sprocket 15 is rotatable upon a vertical axis at the rear end of the cutter bar and serves 45 to actuate the cutter chain 14.

50 Arranged in alignment with the power shaft 7 and journaled in bearings 20 and 21 respectively carried by the housing 8 and by an enlarged sleeve portion 22 keyed to the 55 front end of the power transmitting shaft 7 is a shaft 23 which carries a bevel driving pinion 24 thereon. The sleeve portion 22 is provided with a series of inwardly radially extending ribs 25 and the shaft 23 has splined thereto at 26 a correspondingly ribbed clutch

element 27 which may be connected with the sleeve 22 by an internally grooved, longitudinally movable clutch sleeve 28. The operating mechanism for this clutch sleeve will be subsequently described.

55 The bevel pinion 24 meshes with and drives a bevel gear 30 rotatable upon a vertical axis in advance of and in the same vertical plane with the axis of rotation of the shaft 23. The gear 30 is rigidly mounted upon a hollow

60 shaft 31 journaled in bearings 32 and 33 respectively below and above the gear and carried respectively by a portion of the frame 8 and by a removable cover member 34 detachably held by machine screws 35 to the cover

65 plate 9. Shaft 31 is provided with spur teeth 36 meshing with and driving a large bevel gear 37 which likewise rotates upon a vertical axis. The axis of the bevel gear 37 lies in the

70 same plane with the axes of the shafts 31 and 7 and is in front of the shaft 31 and coaxial with the bearing ring 10. The gear 37 is journaled on ball bearings 38 which surround a shaft 40.

75 The shaft 40 is journaled at its upper end in a ball bearing 41 carried in a removable cover plate 42 and its lower end is journaled in a ball thrust bearing 43 carried by a sleeve member 44 bolted as at 45 to the head 12.

80 The gear 37 is provided with a depending sleeve 46 having permanent clutch teeth 47 at its lower end and interlocking with corresponding permanent clutch teeth upon a radially toothed sleeve member 48 surrounding the shaft 40.

85 Upon a shoulder 50 upon the shaft 40 there rests an externally toothed clutch sleeve 51, the sleeve being keyed as at 52 to the shaft 40. A vertically reciprocable internally toothed clutch member 53 is operative on upward movement to

90 connect the peripheral teeth upon the sleeves 48 and 51 and so to cause the driving of the shaft 40 by the gear 37. The sleeve 53 is provided with a circumferential groove 54 at its upper end with which suitable shifter mechanism, later described, may cooperate.

95 The shaft 40 at its lower end has keyed thereto as at 55 the cutter chain driving sprocket 15 which is held in position by a resilient split ring 56 engaging in a groove 57 surrounding the lower end of the shaft 40.

100 To prevent access of grit or coal dust to the bearing 43 a resiliently mounted sealing ring 58 is arranged in a groove 60 in the lower end of the sleeve member 44 and is held by spring 61

105 in engagement with the upper surface of the cutter chain driving sprocket to provide a seal.

110 For the purpose of swinging the cutter bar appropriate mechanism is actuated by the gear 37. This mechanism includes a pair of vertical shafts 62 and 63 rotating on axes in the same transversely extending vertical

115 plane with the axis of rotation of the shaft 40. The shafts 62 and 63 carry at the upper ends thereof spur gears 64 and 65 suitably keyed

120

125

130

135

140

145

150

to the shafts to effect driving of the latter, the gears 64 and 65 meshing with the gear 37 and being driven by the latter. The gear 64 constitutes the driving element for the shaft 5 on adjusting swinging movement of the cutter bar and the gear 65 the actuating element for the slow or cutting swinging movement of the cutter bar. Coaxial with the gear 64 and rotatable with the shaft 62 is a vertically disposed, multi-thread driving worm 66 (Fig. 4) which engages with a worm wheel 67 (see Fig. 3) rotating upon a transverse axis lying in front of the plane of the axes of rotation of gear 37 and shafts 62 and 63. Co- 10 axial with the shaft 63 and rotating therewith is a worm 68 meshing with a worm wheel 69 coaxial with the worm wheel 67. The lead of the worm 68 is less than that of the worm 66, the ratio of the leads of these worms being 15 appropriate to the desired ratio of cutting and positioning bar swing. The worm wheels 67 and 69 are rotatably supported upon suitable ball bearings 70 upon a transversely extending hollow shaft 71 which is provided 20 between its ends with a worm 72 which constitutes a further driving element in effecting bar swing. The shaft 71 is journaled in bearings 73 at opposite sides of its center and is surrounded to the outside of the bearings 25 73 with suitable means 74 for positioning the ball bearings 70. The inner race of the ball bearing 70 is journaled upon a sleeve 75 splined to shaft 71 and is held against movement in a direction away from the part 74 by 30 a split ring 76. The sleeve 75 is held in position by a locking collar 77 threadedly engaging a reduced portion 78 upon the end of the shaft 71 and a resilient ring 79 serves to prevent accidental backing off of the locking collar. A suitable abutment ring 81 is arranged 35 to the outside of each bearing 70 and the worm wheels 69 and 67 are provided with inwardly directed ribs adapted to engage with friction clutch discs 82 while the sleeve 75 has radially extending ribs 84 engaging with other friction clutch rings interposed between the rings of the first mentioned series. Clutch shippers 87 are arranged outside the 40 series of clutch discs and may be moved in opposite directions to selectively effect engagement of the clutch connecting the worm wheel 67 or the worm wheel 69 to the shaft 71. As previously stated, the shaft 71 is hollow throughout its length, but at one end is provided 45 with a portion of slightly smaller internal diameter. This portion is internally threaded at 90 and is threadedly engaged by a transversely extending rod 91 to whose opposite ends operating handles 92 and 93 are 50 splined and held by machine screws 94. The handles 92 and 93 have sleeves 95 engaging the clutch shippers 87 and upon rotation of the handles in opposite directions force one or the other of the clutch shippers 55 members against the series of discs and so

connect the desired worm wheel in driving relation to the worm 72.

Worm 72 intermeshes with a worm wheel 100 rotating upon a vertical axis in the same vertical longitudinally extending plane with the axes of the shafts 31 and 40. This worm wheel 100 is freely rotatable upon a sleeve 101 surrounding a vertical shaft 102 coaxial with the worm wheel. Shaft 102 is journaled in the bearing 103 adjacent its lower end and in the bearing 104 mounted in a cap 105 bolted at 106 to the cover plate 9. The lower end of the shaft 102 forms a spur pinion 107 which meshes with a large internal spur gear 108 held by bolts 109 to the head 12 and operative on rotation upon its axis, which is in alignment with the axis of the shaft 40, to effect bar swing. Connection of the worm wheel 100 to the shaft 102 is controlled by a vertically reciprocable internally toothed clutch sleeve 111 which is movable downward to effect the clutching of a spur toothed sleeve 112 keyed at 113 to the shaft 102 to the radially extending teeth 114 connected in non-rotative relation to the worm wheel 100. Obviously upward movement of the clutch sleeve 111 disconnects the spur pinion 107 from the worm wheel 100 and permits the free rotation of the latter and so free swinging movement of the cutter bar.

For reasons heretofore set forth it is desirable to first make a power connection to the cutting mechanism gearing, thereafter to effect bar swing if necessary, and only finally to engage the clutch which effects cutter chain driving sprocket rotation. This predetermined sequence of operations is accomplished by rotation of a single handle 120 mounted upon a transversely extending horizontal shaft 121. Shaft 121 carries thereon in non-rotative relation thereto a cam 122 provided with a cam groove 123. This cam groove comprises a plurality of arcuate or non-motion producing portions and a plurality of more nearly chordal portions producing movement of the elements controlled thereby and within the cam groove there are engaged three rollers 124, 125 and 126. The roller 124 is rotatably mounted upon a shaft 127 extending across the slotted end 128 of a longitudinally extending reciprocable clutch shifter bar 129. The bar 129 has a portion 130 engaging in the peripheral groove 131 of the clutch shifter sleeve 28. Roller 125 is rotatably mounted upon a transversely extending shaft 132 which extends between the rearward end of brackets 133 mounted upon the rearward ends of a pair of parallel longitudinally slidable actuating rods 134 which are pivotally connected at their forward ends as at 135 to depending arms 136 rotatably supported by means of sleeve journal members 137 upon the shaft 71. The journal members 137 also carry forwardly projecting parallel arms 138 having portions 139 en-

gaging in the annular groove 140 of the clutch shipper sleeve 111. Roller 126 is journaled upon a shaft 142 connecting the spaced arms 143 of the clutch shipper yoke 144 whose fork 145 operatively engage in the annular groove 54 in the vertically reciprocable cutter chain driving sprocket engaging clutch 53.

From the foregoing it will be obvious that 10 the movements of the roller 124 control the connection of the main power transmitting clutch comprising the elements 27, 28 and 22, that the movements of the roller 125 control the connection of the pinion 107 with the 15 worm wheel 100 and so determine whether the cutter bar shall be free for pivotal movement, or shall be locked or swung by power as may be determined by the operation of the handles 92, 93. The position of roller 126 determines whether or not the cutter chain driving sprocket shall be operatively connected to the driving gear 37.

Starting with the parts in the position shown in Fig. 2, it will be evident that movement of the handle 120 in a counter-clockwise direction will produce no movement whatever of the roller 126 until the handle is rotated through about 120° and that the handle must be rotated a matter of more than 45° before 20 any motion of the roller 125 will take place. After a rotation of a relatively few degrees, however, the roller 124 will begin to be moved. As a result of this disposition of the parts it will be evident that if the handle 120 is moved 25 counterclockwise the clutch sleeve 28 will be moved longitudinally toward the left as the roller 124 moves toward the center of the cam 122 and that after the clutch is fully engaged there will be no further movement of 30 the roller 125. Finally, roller 126 will be subjected to motion toward the center of the cam 35 and as a result the cutter chain driving sprocket will be operatively connected through upward movement of the sleeve 53 40 to the gear 37 and so the cutter chain will be driven. On opposite movement of the cam discs the events mentioned will take place in 45 opposite order but in determined sequence, the cutter chain driving sprocket first being 50 disconnected from its driving element, second, the connection between the worm wheel 100 and the pinion 107 being broken, and, last, the main power connection to the cutting mechanism being interrupted. It will 55 therefore be evident that by no error in opera-

tion can the parts be caused to cooperate in other than the correct sequence and the machine runner and others in the mines will be protected with certainty against accidental injury.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, the combination with a swingable cutter chain carrying cutter bar, of a cutter chain controlling clutch, a cutter bar swing controlling clutch, and a common control for said clutches. 80
2. In a mining machine, the combination with a swingable cutter bar and power actuating means therefor, of a cutter chain controlling clutch, a cutter bar swing controlling clutch, a main power control clutch, and a common control for said clutches. 85
3. In a mining machine, swingable cutting mechanism, and controlling mechanism therefor including a plurality of relatively movable clutches having different controlling functions, one of which controls swinging movement of said cutting mechanism to effect a cutting operation while another controls the actuation of said cutting mechanism, and a common control for successively connecting said clutches including means for connecting said cutting mechanism actuation controlling clutch prior to the connection of said bar swing control clutch. 90
4. In a mining machine, swingable cutting mechanism and controlling mechanism therefor including a plurality of relatively movable clutches having different controlling functions, one of which controls swinging movement of said cutting mechanism to effect a cutting operation, a second of which controls the actuation of said cutting mechanism and a third of which controls the drive through both of said clutches, and a common control for successively operating said clutches. 100
5. In a mining machine, the combination with a swingable cutter chain carrying cutter bar, of a cutter chain controlling clutch, a cutter bar swing controlling clutch, and a common cam control member for actuating said clutches. 110
6. In a mining machine, the combination with a swingable cutter chain carrying cutter bar and power actuating means therefor, of a cutter chain controlling clutch, a cutter bar swing controlling clutch, a main power control clutch, and a common cam member for actuating said clutches. 115
7. In a mining machine, cutting mecha- 120
8. In a mining machine, cutting mecha- 125
9. In a mining machine, cutting mecha- 130

- nism, and controlling mechanism therefor including a plurality of relatively movable clutches having different controlling functions, one of which controls swinging movement of said cutting mechanism to effect a cutting operation, a second of which controls the actuation of said cutting mechanism and a third of which controls the drive through both of said clutches, operating mechanism for each clutch and a common cam control member for actuating said clutches and having a single cam portion for engaging and actuating all of said clutch operating mechanisms for successively operating said clutches. 5
8. In a mining machine, cutting mechanism, and controlling mechanism therefor including a plurality of relatively movable clutches having different controlling functions, one of which controls swinging movement of said cutting mechanism to effect a cutting operation, a second of which controls the actuation of said cutting mechanism and a third of which controls the drive through both of said clutches, operating mechanism for each clutch and a common cam control member for successively operating said clutches and having a single cam portion for engaging and actuating all of said clutch operating mechanisms for successively operating said clutches. 10
9. In a mining machine, the combination with a swingable cutter chain carrying cutter bar, of a cutter chain controlling clutch, a cutter bar swing controlling clutch, and means including a common rotatable control element for actuating said clutches. 15
10. In a mining machine, the combination with a swingable cutter chain carrying cutter bar and power actuating means therefor, of a cutter chain controlling clutch, a cutter bar swing controlling clutch, a main power control clutch, and means including a common rotatable control element for actuating said clutches. 20
11. In a mining machine, the combination with a swingable cutter chain carrying cutter bar and power actuating means therefor, of a main power control clutch, a cutter chain controlling clutch, a bar swing controlling clutch, and means including a common rotatable cam member for actuating said clutches. 25
12. In a mining machine, the combination with a swingable cutter chain carrying cutter bar and power actuating means therefor, of a main power controlling clutch, a cutter chain controlling clutch, a bar swing controlling clutch, and means including a common rotatable cam member for successively actuating said clutches. 30
13. In a mining machine, the combination with a swingable cutter chain carrying cutter bar and power actuating means therefor, of a main power controlling clutch, a cutter chain controlling clutch, a bar swing controlling clutch, and means for successively actuating said 35
- clutch, and a common control for said clutches including means for first actuating said main clutch, for next actuating said bar swing clutch, and for thereafter actuating said cutter chain clutch. 70
14. In a mining machine, the combination with a swingable cutter chain carrying cutter bar and power actuating means therefor, of a main power controlling clutch, a cutter chain controlling clutch, a bar swing controlling clutch, and means for controlling said clutches including a common rotatable cam member for first actuating said main clutch, for next actuating said bar swing clutch, and for thereafter actuating said cutter chain clutch. 75
15. In a mining machine, the combination with a pivoted cutter chain carrying cutter bar and power actuating means therefor, of a main power control clutch, a cutter chain controlling clutch arranged coaxially with the axis of bar swing, and a common control for said clutches. 80
16. In a mining machine, the combination with a pivoted cutter chain carrying cutter bar and power actuating means therefor, of a main power control clutch, a cutter chain controlling clutch arranged coaxially with the axis of bar swing, and means for controlling said clutches including a common rotatable cam member. 85
17. In a mining machine, the combination with a pivoted cutter chain carrying cutter bar and power actuating means therefor, of a main power control clutch, a cutter chain controlling clutch arranged coaxially with the axis of bar swing, and means for successively actuating said clutches including a common rotatable cam member. 90
18. In a mining machine, the combination with a pivoted cutter chain carrying cutter bar and power actuating means therefor including a power shaft, of a main power control clutch arranged coaxially with said shaft, a cutter chain controlling clutch arranged coaxially with the axis of bar swing, and a common control for said clutches. 95
19. In a mining machine, the combination with a pivoted cutter chain carrying cutter bar and power actuating means therefor including a power shaft, of a main power control clutch arranged coaxially with said shaft, a cutter chain controlling clutch arranged coaxially with the axis of bar swing, and means for actuating said clutches including a common rotatable cam member. 100
20. In a mining machine, the combination with a pivoted cutter chain carrying cutter bar and power actuating means therefor including a power shaft, of a main power control clutch arranged coaxially with said shaft, a cutter chain controlling clutch arranged coaxially with the axis of bar swing, and means for successively actuating said 105
- clutches. 110
- 115
- 120
- 125
- 130

clutches including a common rotatable cam member.

21. In a mining machine, the combination with a swingable cutter chain carrying cutter bar, of a cutter chain controlling clutch, a bar swing controlling clutch, and a cam control for successively operating said clutches in fixed sequence.

22. In a mining machine, the combination with a swingable cutter chain carrying cutter bar, of a cutter chain controlling clutch, a bar swing controlling clutch, and a common control for said clutches including means for first actuating said bar swing clutch and thereafter actuating said cutter chain clutch.

23. In a mining machine, controlling mechanism including a plurality of relatively movable clutches, and operating means therefor, and a common control for said clutches including a rotatable element having a single cam groove with which all of said operating means cooperate and operable when rotated in one direction to successively connect said clutches.

24. In a mining machine, controlling mechanism including a plurality of relatively movable clutches and operating means for each of the same including a roller, and a common control for said clutches including a rotatable element having a single cam groove with which said rollers cooperate and operable when rotated in one direction to successively connect said clutches.

25. In a mining machine, kerf cutting mechanism, and controlling mechanism for said cutting mechanism including a plurality of relatively movable clutches having different controlling functions and a common control for said clutches operable when moved in one direction to successively connect all of said clutches and when moved in a reverse direction to successively disconnect the same.

26. In a mining machine, controlling mechanism including a plurality of relatively movable clutches, and operating means therefor, one of said clutches being a cutter drive control clutch, another a cutter swing control clutch and the third a clutch controlling the drive through both of said clutches, and a common control for said clutches including a rotatable element having a single continuous cam means with which all of said operating means cooperate and operable when rotated in one direction to successively connect said clutches.

27. In a mining machine, controlling mechanism including a plurality of controlling clutches having different controlling functions, one of which controls swinging movement of said cutting mechanism to effect a cutting operation, a second of which controls the actuation of said cutting mechanism and a third of which controls the drive through both of said clutches, operating means for

each clutch, and manual controlling means for said clutches including a rotatable control member common to the actuation of all of said clutches, said control member having a single continuous cam means for engaging and actuating the operating means for all of said clutches for successively operating said clutches.

28. In a mining machine, controlling mechanism including three controlling clutches having different controlling functions, one of which controls swinging movement of said cutting mechanism to effect a cutting operation, a second of which controls the actuation of said cutting mechanism and a third of which controls the drive through both of said clutches, operating means for each clutch, and manual controlling means for said clutches including a rotatable control member common to the actuation of all of said clutches, said control member having a single continuous cam means for engaging and actuating the operating means for all of said clutches, the cam surface upon rotation of said control member first effecting the connection of one clutch, secondly another clutch and thereafter the third clutch all in a predetermined sequence.

In testimony whereof I affix my signature.
